UNITED STATES PATENT OFFICE.

THEODORE LOUIS SCHOWENGERDT, OF GEBO, WYOMING.

AUTOMATIC STOP MECHANISM FOR PHONOGRAHS.

Application filed April 16, 1928. Serial No. 270,321.

The present invention relates to improvements in stop mechanisms for phonographs and has for its principal object to provide a means for efficiently stopping the turn table 5 of the phonograph after the reproducer carried by the tone arm has traversed the record supported on the turn table. One of the important objects of the present invention is to provide a stop mechanism for phonographs that can be readily and easily installed without necessitating any material alterations of the parts of the phonograph with which said stop mechanism is adapted to be associated, additional means being provided, for setting the stop mechanism depending upon the particular character of record that is played on the phonograph. A further object is to provide a stop mechanism for phonographs of the above mentioned 10 character whereby the brake can be brought into engagement with the rotatable turn table without causing any injury or disruption of the parts of the stop mechanism that operate automatically. Still a further object is to 15 provide a stop mechanism which is simple in construction, inexpensive, strong and durable and further well adapted to the purpose for which it is designed. Other objects and advantages of the invention will become 20 apparent from the following description when taken in connection with the accompanying drawings.

In the accompanying drawings wherein like reference characters indicate corresponding parts throughout the several views:

Figure 1 is a fragmentary top plan view of the rotatable turn table of a phonograph, showing my improved stop mechanism that 40 is arranged beneath the turn table.

Figure 2 is a sectional view taken approximately on the line 2—2 of Figure 1 showing the stop mechanism in side elevation.

Figure 3 is a detail perspective view of the 45 L-shaped member that cooperates with the depending pin carried by the movable tone arm.

Figure 4 is a detail perspective view of the 50 pivoted lever forming a part of the stop mechanism.

Figure 5 is a similar view of the brake unit, and

Figure 6 is a detail perspective view of the trip and the adjusting rod therefor.

In the drawings wherein for the purpose 55 of illustration is shown the preferred embodiment of my invention, the numeral 1 designates a portion of the rotatable turn table of a phonograph that is mounted in spaced relation upon a suitable support 2, the 60 record engaging pin 3 extending upwardly from the support through the turntable in the manner as clearly shown in the drawing. The turn table is formed at its outer edge with a depending flange 4. The movable 65 tone arm 5 of the phonograph carries a depending pin 6 with which cooperates my improved stop mechanism and the specific construction thereof will now be described. A substantially L-shaped member designated 70 by the numeral 7 is disposed horizontally between the support 2 and the turn table 1 and is pivoted to the support as at 8. The longer arm 9 of this L-shaped member extends outwardly beyond the turn table, and the intermediate portion of this arm is bent upwardly as at 10 so that the outer end portion of this arm will be disposed above the plane of the inner end portion of said arm and as is clearly shown in Figures 1 and 3 of the drawings, the outer end of this arm is formed with a longitudinally extending slot 11 to receive the lower end of the depending pin 6 carried by the movable tone arm 5. Thus the L-shaped member 7 will be adapted for 80 simultaneous movement with the tone arm 5 and the reproducer carried thereby.

An elongated flat rod 12 is secured at its inner end on the upper face of the support 2 adjacent the center of the turn table as at 90 13, and this rod or arm 12 carries at its outer end a cross piece 14, the outer longitudinal edge of which is formed with the ratchet teeth 15 as clearly shown in Figure 1. The outer end of the pivoted rod 12 terminates inwardly 95 of the flanged outer edge of the turn table 1. An elongated link 16 affords an operative connection between the outer end of the shorter arm 17 of the pivoted L-shaped member 7 and the pivoted inner end portion of the rod 12 so 100 that said rod will be actuated on its pivot 13 simultaneously with the swinging movement of the L-shaped member 7. The stop mechanism further includes the provision of a lever

18 that is formed at its inner end with a segmental head portion 19 for disposition beneath the turn table 1 adjacent the outer flanged edge thereof, and this lever is pivoted 5 at its inner end on the support 2, as at 20. The outer end portion of the lever is disposed upwardly and thence laterally to form a handle 21 that is arranged exteriorly of the turn table and a longitudinally extending slot 22 10 is formed in the handle portion 21 for a purpose hereinafter to be more fully described. The curved edge of the segmental head 19 is formed with the teeth 23 that engage with the teeth 24 formed in the curved edge of the segmental inner end portion 25 of the brake carrying plate 26 and this plate is also pivotally supported at its inner end on the support 2 as 15 at 27. A brake element 28 is carried by the outer end of this plate 26 for cooperation with the inner face of the annular flange 4 that depends from the outer edge of the rotatable turn table 1 and the specific construction of the brake unit is more clearly illustrated in Figure 5 of the drawings. A slot 29 20 of arcuate formation is formed in the segmental head portion 25 of this plate 26 and extending upwardly through this slot from the support 2 is a pin 30. A spring 31 is secured at one end to the upper end of the pin 30 and at its other end to the intermediate portion of the plate 26 for normally holding the brake element 28 inwardly and out of engagement with respect to the flange 4 of the turn table 1.

25 A lateral extension 32 is formed on the inner edge of the plate 26 adjacent the segmental head 25 and carried by this extension is the pivoted pawl 33, the same being pivoted intermediate its ends and the inner end of 30 this pawl is adapted for cooperation with the ratchet teeth 15 formed in the outer longitudinal edge of the cross member 14 arranged on the outer end of the pivoted rod 12. A heavy leaf spring 34 is arranged on the plate 26 35 for engagement with the outer end of the pivoted pawl on one side thereof, a lighter spring 35 being disposed on the opposite side of the pivoted pawl as shown very clearly in Figure 5.

40 The springs cooperate to prevent any injury or disruption of the parts of the stop mechanism should the operator forcibly actuate the brake mechanism by hand, the purpose of the light spring being to maintain the pivoted pawl in operative relation with respect to the heavy spring 34. A substantially L-shaped trip member designated generally by the numeral 36 is pivoted at the juncture of the longer arm with the shorter arm on the segmental head 19 of the lever 18, the longer arm 37 extending inwardly and being adapted 45 for cooperation with one end of the toothed cross member 14 on the outer end of the pivoted bar 12. The shorter arm 38 of this L-shaped trip 50 member 36 is pivotally secured to the

inner end of a rod 39 that extends along the upper face of the inner end portion of the pivoted lever 18, the outer portion of this rod being slideable through the vertically disposed portion of the lever through a suitable opening provided therefor in said vertical portion. As is more clearly illustrated in Figure 6 the outer end of this rod 39 is bent upwardly and the upwardly disposed outer end portion of the rod is designated by the numeral 40. The 55 upwardly disposed portion 40 extends through the slot 22 formed in outer end portion of the pivoted lever 18 and threaded on the outer extremity of this portion of the rod is a head 41 that is adapted for slideable movement along the upper face of the outer end portion of the lever.

A spring 42 encircles the upwardly disposed outer end portion 40 of the rod 39 and is disposed between said rod and the bottom 55 of the handle portion 21 of the lever 18 for holding the head 41 against casual sliding movement and furthermore by tightening the head 41 so that the same will be maintained in locked engagement with the handle portion 21 of the lever 18, the trip member 36 may be adjusted with respect to the cross member 14 on the outer end of the pivoted bar 12. The operation of my stop mechanism may be briefly stated as follows. With 60 the parts arranged as shown in Figure 1 of the drawings it will be readily obvious that the L-shaped member 7 will swing on its pivot 8 simultaneously with the movement of the tone arm 5 across the record that is 65 being played and during the swinging movement of the L-shaped member 7 in the direction indicated by the arrow, the pivoted bar 12 will move in the direction indicated by the arrow in Figure 1 so that the end of 70 the cross member 19 that is in engagement with the free end portion of the longer arm 37 of the L-shaped trip 36 will swing the lever 18 on its pivot 20 and the teeth 23 of the segmental head 19 will cooperate with the 75 teeth 24 of the segmental 25 that forms a part of the brake unit to swing the plate 26 outwardly whereby to bring the brake element 28 into engagement with the inner face of the depending flange 4 formed at the outer edge 80 of the turn table 1 whereby said turn table will be brought to a stop, the stopping of the turn table occurring when the reproducer (not shown) that is carried by the movable tone arm has reached the innermost groove 85 of the record that is supported on the turn table. The setting of the stop mechanism to effect the actuation of the brake may be regulated by moving the head 41 inwardly along the handle portion 21 so as to actuate the 90 rod 39 and the latter will in turn move the L-shaped trip member 36 to a predetermined position for cooperation with the cross member 14 carried by the outer end of the pivoted bar 12. In this manner the stop mechanism 95

can be used in conjunction with the playing of records of different makes and sizes. The spring 31 will at all times under normal conditions hold the brake element 28 in an inoperative position and the parts will be returned to their normal positions when the tone arm 5 is swung outwardly to the outer edge portion of the turn table prior to the playing of the record that is placed on the rotatable turn table. The stop mechanism is initially set by swinging the tone arm inwardly whereby to move the arm or bar 12 to the position where it will strike the trip 36 after which the trip is moved part the way back to its proper position. It will thus be seen from the foregoing description that I have provided a stop mechanism for phonographs which will at all times be positive and efficient in its operation and due to its simplicity the stop mechanism can be readily and easily attached to various types of phonographs without necessitating any material alterations of the parts of the phonograph with which the stop mechanism is to be associated. While I have shown the preferred embodiment of my invention it is to be understood that minor changes may be made therein without departing from the spirit of the invention and the scope of the appended claims.

Having thus described the invention, what I claim as new is:—

1. The combination with a phonograph having a turn table, and a tone arm for movement across the turn table; of a stop mechanism for stopping the turn table, said stop mechanism including a pivoted brake unit arranged adjacent the outer edge portion of the turn table and being normally held out of engagement therewith, a lever pivoted adjacent the pivoted brake unit and being operatively connected therewith for simultaneous movement, a trip carried by the pivoted lever for actuating the same, means operable by the tone arm for actuating the trip and move the brake unit into an operative position, said last mentioned means comprising an L-shaped member pivotally supported beneath the turn table, the outer end of the longer arm of said L-shaped member extending beyond the periphery of the turn table and being operatively connected with the movable tone arm for swinging movement therewith, a member pivoted at its inner end beneath the turn table, a cross member at the outer end of the aforesaid member for engagement with the trip, and a link connecting the shorter arm of the L-shaped member with the pivoted end of the member that engages with the trip.
2. The combination with a phonograph having a turn table, and a tone arm for movement across the turn table; of a stop mechanism for stopping the turn table, said stop mechanism including a pivoted brake unit arranged adjacent the outer edge portion of the turn table and being normally held out of engagement therewith, a lever pivoted adjacent the pivoted brake unit and being operatively connected therewith for simultaneous movement, a trip carried by the pivoted lever for actuating the same, means operable by the tone arm for actuating the trip and move the brake unit into an operative position, said last mentioned means including a bar pivoted at its inner end beneath the turn table, the outer end of said bar being in engagement with the trip, and an L-shaped member pivoted beneath the turn table, the outer end of the longer arm of the said L-shaped member extending beyond the outer edge of the turn table and being operatively connected with the movable tone arm, and a link operatively connecting the shorter arm of the L-shaped member with the pivoted end of the bar.

arranged adjacent the outer edge portion of the turn table and being normally held out of engagement therewith, a lever pivoted adjacent the pivoted brake unit and being operatively connected therewith for simultaneous movement, a trip carried by the pivoted lever for actuating the same, means operable by the pivoted lever for actuating the same, means operable by the tone arm for actuating the trip and move the brake unit into an operative position, means carried by said lever for setting the trip, said means including a manually adjustable rod arranged on the lever, said trip including an L-shaped member that is pivoted on the lever, the inner end of the lever being operatively connected with one of the arms of said L-shaped trip.

3. The combination with a phonograph having a turn table, and a tone arm adapted to move across the turn table; of a stop mechanism for stopping the turn table, including a pivoted brake unit arranged adjacent the outer edge portion of the turn table, a turn table engaging brake element carried by the unit and normally held out of engagement with the turn table, a lever pivoted adjacent said unit, the adjacent portions of the brake unit and the lever being formed with toothed segmental head portions that engage with each other to effect the simultaneous movement of said pivoted members, an adjustable trip member carried by the pivoted lever for actuating the latter, means operable by the tone arm for actuating said trip and move the brake element into an operative position, said last mentioned means including a bar pivoted at its inner end beneath the turn table, the outer end of said bar being in engagement with the trip, and an L-shaped member pivoted beneath the turn table, the outer end of the longer arm of the said L-shaped member extending beyond the outer edge of the turn table and being operatively connected with the movable tone arm, and a link operatively connecting the shorter arm of the L-shaped member with the pivoted end of the bar.

4. The combination with a phonograph having a turn table, and a tone arm adapted to move across the turn table; of a stop mechanism for stopping the turn table, including a pivoted brake unit arranged adjacent the outer edge portion of the turn table, a turn table engaging brake element carried by the unit and normally held out of engagement with the turn table, a lever pivoted adjacent said unit, the adjacent portions of the brake unit and the lever being formed with the toothed segmental head portions that engage with each other to effect the simultaneous movement of said pivoted members, an adjustable trip member carried by the pivoted lever for actuating the latter, means operable by the tone arm for actuating said trip and move the brake element into an operative position, said last mentioned means including a bar pivoted at its inner end beneath the turn table, the outer end of said bar being in engagement with the trip, and an L-shaped member pivoted beneath the turn table, the outer end of the longer arm of the said L-shaped member extending beyond the outer edge of the turn table and being operatively connected with the movable tone arm, and a link operatively connecting the shorter arm of the L-shaped member with the pivoted end of the bar.

bar pivoted at its inner end beneath the turn table, the outer end of said bar being in engagement with the trip, and an L-shaped member pivoted beneath the turn table, the outer end of the longer arm of the said L-shaped member extending beyond the outer edge of the turn table and being operatively connected with the movable tone arm, a link

operatively connecting the shorter arm of the L-shaped member with the pivoted end of the bar, and means for manually setting the trip to regulate the movement of the brake element to an operative position. ¹⁰

In testimony whereof I affix my signature.

THEODORE LOUIS SCHOWENGERDT.
